UNITED STATES PATENT OFFICE.

ARTHUR KORN, OF MUNICH, GERMANY.

TELAUTOGRAPH.

No. 851,174.

Specification of Letters Patent.

Patented April 23, 1907.

Application filed January 25, 1907. Serial No. 854,082.

To all whom it may concern:

Be it known that I, ARTHUR KORN, a citizen of the Empire of Germany, residing at Munich, in the Empire of Germany, have invented a new and useful Telautograph, of which the following is a specification.

My invention relates to improvements in telautographic systems, whereby the speed in the production at the receiving station of a copy of an original at the sending station is considerably increased.

The chief improvement consists in the employment at the receiving station of a galvanometer with an interceptor on one or two parallel metallic strings as conductors for controlling a ray of light acting upon a sensitive film or the like.

I will now proceed to describe my invention with reference to the accompanying drawings, in which—

Figure 1 is a vertical longitudinal section through a galvanometer with an interceptor on two parallel metallic strings on the line E—F in Fig. 2, Fig. 2 is a horizontal section 15 through the same on the line A—B in Fig. 1, Fig. 3 is a side view of the lower part of the same, seen from right to left in Fig. 1, Fig. 4 is a vertical cross section through the line C—D in Fig. 1, the metallic strings occupying 20 their upper extreme position, Fig. 5 is a similar cross section, the metallic strings occupying their lower extreme position, Fig. 6 is a plan of a receiver, parts being shown in section, Fig. 7 is a plan of a sender, Fig. 8 is a 25 diagram of a telautographic system, Fig. 9 is a diagram of a modified telautographic system, Fig. 10 is a vertical longitudinal section 30 on the line G—H in Fig. 11 through part of a galvanometer with an interceptor on a single 35 metallic string serving as a conductor, Fig. 40 11 is a horizontal section through the same on the line I—J in Fig. 10, and Fig. 12 is a diagram of a simplified telautographic system.

Similar characters of reference refer to 45 similar parts throughout the several views.

I preferably employ a galvanometer, which is illustrated in Figs. 1 to 5. 1 denotes a horseshoe magnet, the poles of which are provided with two opposite cross holes 2, 2 in the 50 same central line. Between the two poles of the magnet 1 a rectangular frame 3 of timber or the like and of any suitable known construction is disposed and secured in any known manner, for example by means of 55 screws 4, 4. A metallic strap 5 is fastened

on the left short side (Figs. 1 and 2) of the frame 3 and is provided with a horizontal cross pin 6 within and with a suitable binding post 7 without. A longitudinally bored metallic piece 8 is fastened on the right short 60 side of the frame 3 and is provided with a binding post 9. A movable metallic strap 10 is disposed within the frame 3 and is guided between suitable pieces 11, 11 of timber or the like. It is provided with a horizontal 65 cross pin 12 and a screw threaded shank 13, which latter is guided in the bore of the piece 8 and can be longitudinally shifted by means of a winged nut 14. A thin doubled metallic wire 15, 16 is passed round the pin 6 and its two ends are soldered or otherwise fastened on the other pin 12. The two pins 6 and 12 having the same diameter, it will be understood, that the two wires 15 and 16 will be parallel to each other. The two wires 15 and 16 are to serve as conductors. A thin little plate 17 impermeable to light, say of aluminium or other opaque material, is stuck to the two wires 15 and 16 in the vertical central plane of the two holes 2, 2 and serves as 70 an interceptor as will be hereinafter described. By means of the winged nut 14 the two wires 15 and 16 can be more or less and uniformly tightened. When an electric current of a sufficient strength passes through the two 75 conductors 15 and 16 in one direction, say from the line 19 to the line 18, the aluminium plate or interceptor 17 will be shifted upward into an extreme upper position as is shown in Fig. 4. On the other hand, if the electric 80 current passes through the two conductors 15 and 16 in the opposite direction, say from the line 18 to the line 19, the aluminium plate or interceptor 17 will be shifted downwards into an extreme lower position as is shown in 85 Fig. 5. By means of the winged nut 14 it is possible to so adjust the tension of the two wires 15 and 16 with regard to the strength of the current, that the two extreme positions of the aluminium plate or interceptor 17 shall 90 be at a certain vertical distance from each other, as will be hereinafter described. For attaining this object it may be that the strength of the current passing in the one direction requires to be larger than that of the 95 opposite current. This will have to be ascertained by trials. The conductors 15 and 16 may also be metallic threads or thin and narrow metallic strips or ribbons.

The galvanometer described I employ at a 100

receiving station for controlling a ray of light acting upon a sensitive film or the like as follows:

Fig. 6 illustrates a receiver. 20 denotes a box of any known construction, which is closed and made impermeable to light. In this box 20 a horizontal screw-spindle 21 is fastened, on which a platen-roll 22 rigidly connected with a gear wheel 23 is made to fit. 5 A horizontal long pinion 24 is mounted in the box 20 to turn and meshes with the gear wheel 23. The pitch of the screw-spindle 21 is such, that the platen-roll 22 with the gear wheel 23 is longitudinally shifted through a minute distance during every revolution. 10 The box 20 may be connected with a casing or frame 25, in which a clockwork of any known construction is disposed. In Fig. 6 this clockwork is shown as comprising a spring barrel 26 loose on a winding shaft 27 and rigidly connected with a gear wheel 28, which is adapted to drive the long pinion 24 by means of its shaft and a pinion 29 and also a fly 30 by means of its shaft 31, a pinion 32, a gear wheel 33, its shaft 34 and a pinion 35. A ratchet wheel 36 is fastened on the winding shaft 27 and is checked by a spring-pressed pawl 37. It will be understood, that by means of a key put on the square 27¹ of the winding shaft 27 the spring within the barrel 26 can be wound up and that on the fly 30 being released by some known means (not shown) the clockwork will be put in motion to drive the platen-roll 22, which will rotate and will be gradually shifted on the screw-spindle 21 in its longitudinal direction. 30

At a convenient distance from the box 20 the galvanometer above described is disposed on some base (not shown). Between this 40 galvanometer and the box 20 a tube 38 of any known construction is placed on some support or feet (not shown). The tube 38 may have a conical tubular end piece 39, which is embedded in a suitable boss 40 on the box 20 and is provided with a bottom. In the middle of this bottom a fine hole 41 is made. The tube 38 is provided with two lenses 42 and 43 of any known construction, either simple or compound, and may have a 45 bottom with a hole 44 of about the same diameter as the holes 2, 2 in the poles of the horseshoe magnet 1. On the other side of the latter another tube 45 of any known construction is disposed in line with the tube 38 and on some support or feet placed on the said base. The tube 45 contains some source of light, for example an incandescent electric lamp 46, at the external end and a lens 47 intermediate its two ends and may 50 have a bottom with a hole 48 at the internal end. The lamp 46 supplied with current from some source (not shown) will emit rays of light, a part of which will be collected by the lens 47 and be sent forward in a converging pencil through the holes 48 and 2, the

frame 3 and the other hole 2. After their passage through the focus 49 (Fig. 5) the rays will go forward in a diverging pencil and will be collected by the lens 42. The latter will send the rays to the third lens 43, which will collect and send them toward the platen-roll 22. The focus 49 is preferably placed in the plane of the little aluminium plate or interceptor 17 and should be so disposed, that the little aluminium plate or interceptor 17 in its one extreme position, say the lowermost position in Fig. 5, will permit the rays of light to pass freely from the left to the right in Fig. 6, while in its other extreme position, say the uppermost position, the little aluminium plate 17 will intercept the converging pencil of rays of light, as is shown in Fig. 4, the rays of light being in both cases indicated by the dotted lines. The focus 49 may also be somewhere near the 85 little aluminium plate or interceptor 17, the only condition being, that the latter be able in its one extreme position to intercept and in its other extreme position to permit the rays of light to pass. The lens 42 may be so 90 arranged as to produce on the third lens 43 a real image of the aluminium plate or interceptor 17 in its uppermost position. In this case of course no light will pass through the lens 43 and the camera obscura formed by the conical piece 39. If the aluminium plate or interceptor 17 occupies its lowermost position shown in Fig. 5, of course the lens 43 will be fully lighted, so that a ray of light (indicated by the dotted line in Fig. 6) 95 will pass through the fine hole 41 and will strike the platen roll 22. A sensitive film 50 or paper or the like is placed round the cylinder 22 and is fastened thereon in any known manner and it will be understood, that the 100 ray of light will produce an impression on this film 50 or the like. The focus of the pencil of rays of light in the camera obscura 39 may be on the circumference of the cylinder 22, as may be seen from Fig. 6, but this 105 is not absolutely necessary. The central line of the two tubes 38 and 45 may be placed at right angles to the axis of the platen-roll 22 and may be made to cut this axis. The 110 said central line should be so disposed with regard to the box 20, that the ray of light may meet every point of the sensitive film 50 or the like from its one border to its other border or nearly so during the rotation and longitudinal motion of the platen-roll 22. 115

At the sending station a sender of any known construction is disposed. This sender may also be similar to the receiver above described, only that the galvanometer with the device for projecting a ray of light on the platen-roll 22 is omitted, as is shown at Fig. 7, in which similar parts are denoted by the same characters of reference as in Fig. 6. The box or casing 20 needs not be closed or impermeable to light. A writing pen 51 of 120

any known construction (see Figs. 8 and 9) and serving as a transmitting tracer is mounted to rock in suitable supports 52 on the casing 20 and is electrically connected with a line 53. This pen 51 is adapted to press on an original 54, which is placed round the platen-roll 22 and is fastened thereon in any known manner. The original may be a manuscript or a drawing or a picture or a half-tone engraving, of which the several lines, dots, points and other features are drawn or produced with an insulating ink or the like on a metallic foil. The screw-spindle 21 is connected with a binding post 55, to which a line 56 can be attached. The platen-roll 22 is preferably insulated from the gear wheel 23 and is electrically connected with the line 56. It will now be understood, that when the platen-roll 22 is inserted in a circuit and put into motion the transmitting tracer 51 will normally close the circuit and will open the same only, when its point meets a line, dot, point or other feature of the original.

A system for connecting the two stations is diagrammatically illustrated in Fig. 8. A source of current 57 is disposed at the sending station and is connected with the sender say by the line 56 and may be connected with the receiving station on the right by a line of transmission 58. The sender may be connected with the receiving station by a line of transmission 63 and the line 53. However, either of the two lines of transmission 58 and 63 may be replaced by earth plates and the earth, as is well known: I desire it expressly to be understood, that the term "electrical connections," which I employ in the following claims, may include either two wire conductors between the two stations or a wire conductor on the one hand and the earth on the other hand between the two stations. At the receiving station an adjustable resistance 62 and a source of current 60 are disposed and are connected in series by a line 61. The adjustable resistance 62 is connected with the line of transmission 63 and the source of current 60 is connected with the line of transmission 58 by a line 59. The line 18 of the galvanometer may be connected with the lines 58 and 59 and the line 19 with the resistance 62. It will be seen, that the system forms a Wheatstone bridge in the bridge of which the conductors of the galvanometer are inserted. Means are provided at both stations for so controlling the two clockworks of the sender and the receiver respectively, that the two platen-rolls 22 and 22 are caused to move synchronously, impulses being periodically sent through the circuit of the two batteries 57 and 60. I do not show or describe any means for synchronising the two clockworks, as they may be of any known construction and as it is well known, that the two platen-rolls 22 and 22 will require to be synchronised.

After the above explanations the manner of operating the system will be obvious. As long as the transmitting tracer 51 closes the circuit, a current from both batteries 57 and 60 will pass from the battery 57 through the line 56, the platen-roll 22, the transmitting tracer 51, the lines 53 and 63, the resistance 62, the line 61, the battery 60 and the lines 59 and 58 back to the battery 57, while at the same time a part of the current will pass through the bridge, that is the line 19, the two conductors 15 and 16 and the line 18. The consequence of this will be, that the little aluminium plate or interceptor 17 will occupy its uppermost position (Fig. 4) and intercept the pencil of rays of light, so that no ray of light is permitted to act upon the sensitive film 50 or the like. The moment, however, the transmitting tracer 51 at the sending station comes in contact with some insulating line, dot, point or other feature of the original 54, it will break the circuit of the battery 57, so that a current from the battery 60 alone will pass through the lines 59 and 18, the two conductors 15 and 16, the line 19, the resistance 62 and the line 61 back to the battery 60. The consequence of this will be, that the little aluminium plate or interceptor 17 will be shifted into its lowermost position (Fig. 5) and will permit the rays of light to pass to the lenses 42 and 43, so that a ray of light will pass through the fine hole 41 and act upon the sensitive film 50 or the like. When the transmitting tracer 51 again closes the circuit of the battery 57, the little aluminium plate or interceptor 17 will return to its uppermost position and intercept the rays of light.

The system illustrated in Fig. 8 may be modified in that at the receiving station the source of current 60 is replaced by a small one 64 inserted in the bridge, as is shown at Fig. 9. The operation of the galvanometer will in this case be much the same as before. When the transmitting tracer 51 at the sending station closes the circuit of the battery 57, a current will pass from the latter through the line 56, the platen-roll 22, the transmitting tracer 51, the lines 53 and 63, the resistance 62 and the lines 61 and 58 back to the battery 57, while at the same time a part of the current will pass from the resistance 62 through the line 19, the two conductors 15 and 16, the battery 64 and the line 18 to the line 58 while counteracting the electromotive force of the battery 64. The consequence of this will be, that the little aluminium plate or interceptor 17 will be kept in its uppermost position (Fig. 4) and will intercept the rays of light from the source 46. The moment the transmitting tracer 51 comes in contact with some insulating line, dot, point or other feature of the original 54, it will break the circuit of the battery 57, so that the circuit of the small battery 64 at 130

the receiving station alone remains closed. Then a current will pass from the battery 64 through the two conductors 15 and 16, the line 19, the resistance 62 and the lines 61 and 18 back to the battery 64. The consequence of this will be, that the little aluminium plate or interceptor 17 will be shifted into its lowermost position (Fig. 5) and will permit the rays of light to pass to the lens 43, so that 10 a ray of light passing through the fine hole 41 will act upon the sensitive film 50 or the like. The image produced by the impression of the ray of light on the sensitive film 50 or the like can be developed in the usual 15 manner.

The galvanometer of the kind described above is particularly suitable for the telautograph, since the mass to be actuated in both directions is minimal and is checked in 20 its motion merely by the tension of the two metallic strings and not at all by means of stops to which it might stick. Thereby it is rendered possible to exert in the two metallic strings 15 and 16 a dynamic force for exceeding 25 the directing force of the strings. In fact the dynamic force may be made so great as to render the directing force of the strings 15 and 16 insignificant in proportion to it. Thereby an exceedingly high speed in the 30 production of the image at the receiving station is obtained, which speed only depends on the speed of the variations of the current.

The galvanometer may be varied in many respects. For example the two strings 15 and 16 in Fig. 1 may be replaced by a single thin metallic strip or ribbon 65, from which the little aluminium plate or interceptor 17 is suspended, as is shown at Figs. 10 and 11. In Fig. 10 the lower extreme position of the 40 interceptor 17 and the conductor 65 is shown in full lines, while their upper extreme position is indicated by dotted lines. The two ends of the metallic strip 65 may be fastened in slits of two rods 66 and 67 respectively by 45 soldering or otherwise. The rod 66 may have near its internal end a collar 68 and a square part 69 and at its external end a screw-thread 70. The collar 68 may bear against a metallic plate 72 on the inside of 50 the frame 3 and the square part 69 may engage in a square hole in the plate 72 to prevent the rod 66 from turning. The rod 66 may be secured in the frame 3 by means of a nut 71 on its screw-threaded end 70. The nut 55 71 may be rigidly connected with a binding post 73 by means of an arm and the binding post 73 may be connected with the line 19 mentioned above. The rod 67 on the right in Fig. 10 may have a square collar 74, which 60 may be guided between two parallel plates 75, 75 in the frame 3, so as to prevent the rod 67 from turning. Otherwise the construction of the galvanometer is the same as before. It is immaterial, what shape the interceptor 65 65 is given. It may be a hollow

ball or otherwise shaped. I prefer to employ a thin little plate, so as to render the mass of the interceptor 17 and the conductor 65 or conductors 15 and 16 as minimal as possible. The two parallel conductors 15 and 16 shown in Fig. 1 may be preferable to the single conductor 65 shown in Fig. 10 for the reason that they may be better able to hold the little plate 17 parallel to the legs of the horseshoe magnet 1. 75

The device for projecting a ray of light on the sensitive film, paper and the like may be varied in many respects and I do not limit myself to the construction shown and described. 80

Where so preferred, the telautographic system illustrated in Fig. 8 may be simplified by omitting the battery 60 and the lines 59 and 61, as is shown at Fig. 12. In this case the galvanometer will require to be so arranged, that its interceptor 17 normally occupies its lowermost position and is shifted upward only if a current passes through its single conductor 65 or its two parallel conductors 15 and 16. If the original on the 90 platen-roll 22 at the sending station be made as before, that is to say, if it be a manuscript or a drawing or a picture or a half-tone engraving, of which the several lines, dots, points and other features are drawn or produced with an insulating ink or the like on a metallic foil, of course the transmitting tracer 51 will normally close the circuit, so that the interceptor 17 will occupy its uppermost position and intercept the rays of light 100 (see Fig. 4). The moment the transmitting tracer 51 comes in contact with some insulating line, dot, point or other feature of the original 54, it will break the circuit, so that the conductor 65 or conductors 15 and 16 105 will be without current and will drop, whereupon the interceptor 17 will permit the rays of light to pass to the lens 43, so that a ray of light passing through the fine hole 41 will act upon the sensitive film 50 or the like. 110 However, I prefer to employ either of the two systems illustrated in Figs. 8 and 9 in opposition to the simplified system shown in Fig. 12. 115

Evidently the galvanometer may be so arranged, that the central line of the two tubes 38 and 45 passes through the interceptor 17 in that of its two extreme positions, in which it permits the rays of light to pass from the source 46 to the lens 43, so that normally a 120 ray of light will act upon the sensitive film, paper or the like, as long as the circuit 57, 56, 22, 51, 53, 63, 62, 61, 60, 59 and 58 in Fig. 8 or the circuit 57, 56, 22, 51, 53, 63, 62, 61 and 58 in Fig. 9 or the circuit 57, 56, 22, 51, 53, 63, 62, 19, 15 and 16 or 65, 18 and 58 in Fig. 12 is closed. Only if the circuit is broken, the interceptor 17 will intercept the rays of light. The result will be a negative photograph of the original. For the system 130

shown in Fig. 12 the central line of the tubes 38 and 45 would in this case require to pass through the interceptor 17 in its lowermost normal position in Fig. 10, which means that 5 the frame 3 would require to be shifted upward through such a distance, that the said central line passes through the centers of the two cross holes 2, 2 in the poles of the horseshoe magnet 1.

10 I claim:

1. In a telautographic system, the combination with a transmitting tracer and its platen-roll, of a receiving platen-roll, a device for projecting a ray of light on said receiving platen-roll, a galvanometer comprising a horseshoe magnet, a frame between the poles of said horseshoe magnet, a conductor stretched therein and an interceptor on the middle of the conductor, said interceptor being adapted to render said device operative and inoperative, and electrical connections between said transmitting tracer and its platen-roll on the one hand and the conductor of said galvanometer on the other hand, 25 said transmitting tracer being adapted to open and to close the circuit.

2. In a telautographic system, the combination with a transmitting tracer and its platen-roll, of a receiving platen-roll, a device for projecting a ray of light on said receiving platen-roll, a galvanometer comprising a horseshoe magnet, a frame between the poles of said horseshoe magnet, a conductor stretched therein and an interceptor on the middle of the conductor, said interceptor being adapted to render said device operative and inoperative, and electrical connections between said transmitting tracer and its platen-roll on the one hand and the receiving station on the other hand and forming a 35 Wheatstone bridge, in the bridge of which the conductor of said galvanometer is inserted, said transmitting tracer being adapted to open and to close the circuit.

40 3. In a telautographic system, the combination with a transmitting tracer and its platen-roll, of a receiving platen-roll, a de-

vice for projecting a ray of light on said receiving platen-roll, a galvanometer comprising a horseshoe magnet, a frame between the poles of said horseshoe magnet, a conductor stretched therein and an interceptor on the middle of the conductor, said interceptor being adapted to render said device operative and inoperative, a circuit including the conductor of said galvanometer, and electrical connections between said transmitting tracer and its platen-roll on the one hand and said circuit on the other hand, whereby a Wheatstone bridge is formed, in the bridge of which the conductor of said galvanometer is inserted, said transmitting tracer being adapted to open and to close the circuit.

4. In a telautographic system, the combination with a transmitting tracer and its platen-roll, of a receiving platen-roll, a horseshoe magnet having two cross holes in its two poles, a frame between the poles of said horseshoe magnet at right angles to its cross holes, a conductor stretched in said frame and provided in its middle with an interceptor, means for regulating the tension of said conductor, means for projecting rays of light through the cross holes of said horseshoe magnet toward said receiving platen-roll, 75 said interceptor being adapted to intercept in its one extreme position and to permit in its other extreme position the rays of light to pass, means for permitting of the rays of light only a single one to strike said receiving platen-roll, a circuit including said conductor, and electrical connections between said transmitting tracer and its platen-roll on the one hand and said circuit on the other hand, whereby a Wheatstone bridge is formed, in the bridge of which said conductor is located, said transmitting tracer being 80 adapted to open and to close the general circuit.

ARTHUR KORN.
